UNITED STATES PATENT OFFICE.

RUDOLF EICKEMEYER, OF YONKERS, NEW YORK.

SPEAKING-TELEPHONE.

SPECIFICATION forming part of Letters Patent No. 230,698, dated August 3, 1880.

Application filed May 10, 1880. (No model.)

To all whom it may concern:

Be it known that I, RUDOLF EICKEMEYER, of Yonkers, in the State of New York, have invented a new and useful Improvement in 5 Speaking-Telephones, of which the following is a specification.

My invention relates to a new form of transmitting-instrument for the electrical speaking-telephone. The instrument embraces a mag- 10 neto-electric apparatus for generating an electric current by the movement of the armature of a magnet in its magnetic field of force. The power to move the armature may be supplied by a weight or spring or directly by the hu- 15 man hand.

The instrument also embraces a telephone-disk or vibrating plate to receive the sound-waves, and, by its vibrations under such waves, to control or vary the power exerted on the 20 armature of the electro-magnet for generating a current in the telephone-circuit. In this instrument the force of the sound-waves falling upon the disk does not act to vary the resistance of an electric circuit through which a 25 current is flowing, nor directly to move the armature of an electro-magnet, and thus generate a current in a telephone-circuit; but it acts to vary the amount of force exerted by the weight or spring or other source of power upon 30 the armature, and it does this by increasing or diminishing the friction between a revolving wheel and a rod or lever resting against it and connected with the armature by the movement of which the current is generated.

35 In the drawings, Figure 1 is a front elevation of an instrument embodying my invention. Fig. 2 is a sectional elevation on the line xx of Fig. 1. Fig. 3 is a sectional elevation on the line $x'x'$ of Fig. 1. Fig. 4 is a plan with 40 the mouth-piece and diaphragm shown in section on the line x^2x^2 of Fig. 1. Fig. 5 is a plan with the driving-shaft, key, and mouth-piece removed. Figs. 6, 7, 8, and 9 are enlarged views, illustrating some of the details 45 of construction.

A is a wooden frame, upon the upright portions of which is mounted a slotted bed-plate A' . B is a shaft having bearings in brackets aa , which are screwed to the bed-plate A' , and 50 having an enlargement, B' , which, in turn, has a V-shaped friction-groove, v . The shaft B is

revolved by a crank-wheel, C, on shaft C' , which carries a pinion, c , taking into a gear-wheel, b , on shaft B. D is the mouth-piece, of the ordinary funnel shape. D' is an adjustable rectangular bracket secured to the bed-plate A' by screws $d d$ passing through slots in the horizontal part of the bracket. 55

Between the perpendicular part of the bracket D' and the mouth-piece D is clamped the dia- 60 phragm o in such manner that its center is as near as may be in a horizontal plane which, if continued, would bisect the shaft B, and at the same time is in a perpendicular plane which, if continued, would bisect the V-shaped 65 groove v .

E is an adjustable plate, secured to the bed-plate A' by screws $d' d'$ passing through slots in the plate E; and to the plate E is secured by a screw, d^2 , a rectangular wooden block, F, 70 in the side faces of which are inserted two binding-screws, $s' s^2$. To the upper face of the block F, by means of a plate, t , and screws d^3 , d^3 , is clamped the rear end of a broad spring, e .

K is a key fitting nicely in the groove v of 75 the shaft B. It is a hinged at one end to the center of the diaphragm, as best shown in Figs. 6 and 7, and near the other to a post, p , the broad base of which rests on spring e .

J is an induction-coil, held in position in part 80 by having the lower flange of its spool fitted into the block F and in part by a strap, l .

The core r of the induction-coil J consists of a number of pieces of soft iron within a tube, the whole being secured to the lower face of 85 the spring e , as shown.

M is a permanent magnet made up of several magnetic bars clamped together, as shown, and supported by a bracket, G, which is secured to the adjustable plate E. 90

Between the bars of the magnet M, at the upper end, is inserted a soft-iron plate, r' , the upper portion of which forms a core for a second induction-coil, J' , the spool of which fits tightly upon the core. 95

In front of the magnet M is a hard-rubber plate, P, secured to the bracket G by two screws passing through a plate, n , as shown, and in this plate are two binding-screws, $s^3 s^4$.

The outer end of the wire of induction-coil 100 J is connected with the inner end of the wire of induction-coil J' by means of binding-screws

^{s²} ^{s³}, which are connected by an independent wire, and the inner end of coil J is connected with the ground by means of binding-screw ^{s'}, while the outer end of coil J' is connected with the line-wire by means of binding-screw ^{s⁴}.

The mode of operation is as follows: The operator speaks at the mouth-piece in the usual manner, and at the same time the crank-wheel is turned. In the normal adjustment of the instrument the motion of the shaft B has a tendency to send the key K downward, carrying with it the post *p*, spring *e*, and core *r*, while the spring *e* has a tendency, and nearly, although not quite, the requisite strength, to carry the key back to its normal position in the groove, and at the same time lift the core *r*, which has a free up-and-down movement within its coil J. This movement creates by induction a current in coils J and J', and consequently in the line-wire. The vibrations of the diaphragm, caused by sound-waves falling upon it, constantly modify the frictional contact between the key K and the groove *v*, and there is a corresponding modification in the length and speed of the movements of the core *r* within the coil J. Therefore, while the crank is turned and the operator talks at the mouth-piece, a current traverses the line-wire, varying in strength with the movement of the dia-

phragm in such manner that the sounds uttered will be reproduced in a proper receiving-instrument.

The adjustment of the plate D' is controlled by screws ^{d⁴} and ^{d⁵} in a projection from the lower edge of the front face of that plate, the screws ^{d⁴} entering the bed-plate A', while the screws ^{d⁵} bear against the edge of the bed-plate A'.

A spring, *w*, which is adjusted by a set-screw, *y*, maintains the required initial pressure between the key K and the groove *v*. This method of regulating the initial pressure relieves the diaphragm from unnecessary strain.

I claim—

1. A transmitting-instrument for the electric telephone in which the sound-waves falling upon the instrument are made to vary the force exerted by a spring, weight, or other source of power to move the armature of an electro-magnet and generate a current in a telephonic circuit.

2. The adjustable spring *w*, so arranged as to maintain the required initial pressure between the key K and the groove *v*, substantially as described.

R. EICKEMEYER.
